CLAIM

We claim the ornamental design for a steamer plate, as shown and described.

DESCRIPTION

FIG. 1 is a top front perspective view of a steamer plate according to the new design.

FIG. 2 is a bottom perspective view of the steamer plate shown in FIG. 1.

FIG. 3 is a right side view of the steamer plate shown in FIG. 1.

FIG. 4 is a left side view of the steamer plate shown in FIG. 1.

FIG. 5 is a front view of the steamer plate shown in FIG. 1. FIG. 6 is a back view of the steamer plate shown in FIG. 1. FIG. 7 is a top view of the steamer plate shown in FIG. 1; and,

FIG. 8 is a bottom view of the steamer plate shown in FIG. 1.
